UNITED STATES PATENT OFFICE.

TURNER HUNT NANCE, OF BIRMINGHAM, ALABAMA, ASSIGNEE, BY MESNE ASSIGNMENTS, TO NATIONAL UTILITIES COMPANY, OF BIRMINGHAM, ALABAMA, A CORPORATION OF ALABAMA.

DRY CLOSET.

1,186,821.

Specification of Letters Patent. Patented June 13, 1916.

Application filed April 5, 1915. Serial No. 19,256.

To all whom it may concern:

Be it known that I, TURNER H. NANCE, a citizen of the United States, residing at Birmingham, in the county of Jefferson and 5 State of Alabama, have invented a new and useful Dry Closet, of which the following is a specification.

This invention has reference to dry closets and its object is to provide a dry closet 10 which when not in use may be moved to the exterior of a room or building, and may be drawn into the room or building into position for use.

In accordance with the present invention 15 there is provided a substantially closed receptacle or compartment communicating with the interior of the room or building through an opening normally closed by a door. Within the receptacle there is normally lodged a box or casing housing a removable container. On the opening of the door to the receptacle, which door is within the room or building, the box or casing is 20 accessible and may be then drawn into the room or building for use. To assure the return of the box to the receptacle gravity 25 or other suitable propelling means are provided.

The receptacle exterior to the room or 30 building has ventilating means and ventilating openings may extend to the interior of the room so that all air currents move from the room into the receptacle and from the latter to some suitable point of disposal, 35 which in the case of a dwelling may be at or above the roof.

The invention will be best understood 40 from a consideration of the following detailed description, taken in connection with the accompanying drawings forming a part 45 of this specification, with the further understanding that while the drawings show a practical form of the invention, the latter is not confined to any strict conformity with the showing of the drawings, but may be changed and modified so long as such changes and modifications mark no material departure from the salient features of the 50 invention.

50 In the drawings:—Figure 1 is a front elevation, with some parts broken away and some parts in vertical section, of a dry closet embodying the present invention. Fig. 2 is a longitudinal vertical section of

the structure of Fig. 1 with some parts in 55 elevation and also showing in dotted lines the position assumed on the opening of the receptacle and the withdrawal therefrom of the box or casing. Fig. 3 is a section on the line 3—3 of Fig. 2. Fig. 4 is an elevation 60 similar to Fig. 1 but showing another form of the invention. Fig. 5 is a vertical front 65 to rear section of the structure of Fig. 4 with some parts in elevation and showing in dotted lines the position assumed when the 70 box or casing is drawn out for use. Fig. 6 is a section on the line 6—6 of Fig. 5.

In the drawings there is shown a wall 1 and a floor 2. The wall 1 may be taken as indicative of the outer wall of a building, and 70 the floor 2 may be taken as indicative of the floor of a room within the building, or the wall 1 may be taken as a division wall between the room and some other compartment or space exterior to the room on the 75 opposite side of the wall 1. For convenience of description the wall 1 will be considered as the outer wall of a building. Through the wall 1 on about or slightly above the level of the floor 2 is a passage 3 80 and projecting through the lower part of this passage to the exterior of the building and for an appropriate distance beyond the wall 1 is a shelf 4. Inclosing the shelf 4 and projecting a corresponding distance beyond the outer face of the wall 1 is a casing 5 which may be made of metal, either galvanized iron or some other appropriate metal suitably protected from the effects of 85 weather. The casing 5 projects into the 90 opening 3 to about the inner edge of the opening, and is of about the same area as the passage 3, except that the casing 5 is not quite as high as the passage 3, leaving a small section of the passage 3 above the top 95 of the casing 5 where lodged within the passage 3. The top of the casing 5 indicated at 7 slants away from the wall 1 so as to conveniently shed water, especially where the casing 5 is exterior to a building. 100 Through the top 7 is a hole 8 surrounded by a collar 9 to which is attached the lower end of a vent pipe 10 which may rise to any convenient height and be provided with any convenient means for aiding in the production of an up-draft through the vent pipe 10. 105

The outer end of the casing 5, that is, the end remote from the wall 1, is provided

with a slide 11 normally in the closed position, but this slide may be raised to permit access to the casing 5 from outside of the building.

5 Since the sides of the casing 5 are designed to support certain structures such sides indicated at 12 may be formed of wood or other like material instead of these sides being formed of sheet metal, but this does 10 not preclude the formation of the casing 5 wholly of sheet metal. When the sides 12 are made of wood or some such material, the slide 11 may have its edges seated in grooves 13 in the outer ends of the sides 12. 15 For convenience of manipulation the slide 11 is provided with a handle 14 at its upper end, it being understood that the slide 11 moves up and down and that the shelf 4 is horizontal or approximately so.

20 Hinged to the inner edge of the shelf 4 which terminates within the building is a door 15 of a height and breadth to effectively cover the passage 3. The door is secured to the inner edge of the shelf 4 by hinges 25 16 so that the door may open downwardly into substantially parallelism with the floor 2, a knob 17 being provided for the manipulation of the door, and such knob, or more than one knob if desirable, will provide a 30 convenient support for that end of the door when down remote from the shelf 4. When the door has been opened and laid out substantially flat, the upper surface of the open door, corresponding to that surface 35 of the door presented toward the passage 3 when the door is closed, constitutes a continuation of the upper surface of the shelf 4. Near the sides of the shelf 4 it has produced in its upper surface grooves 18 and 40 the door 15 has similar grooves 19 in that surface presented toward the passage 3, the grooves 19 alining with the grooves 18 when the door is opened and laid flat.

45 That surface of the door 15 toward the room into which the passage 3 opens may have a covering 20 of configuration or suitably ornamented, as indicated in Fig. 1, so that so far as appearance goes the door when closed simulates a covered fire place, 50 or some other structure often found in rooms. The ornamental effect may be further produced by paneling 21 adjacent to the space occupied by the closed door.

Normally lodged within the casing 5 is 55 a box 22 mounted on wheels 23 adapted to the grooves 18 and 19, so that the box is readily moved from its normal position within the casing 5 into the room when the door 15 is opened and laid flat. The grooves 60 19 terminate as shown at 24 at such point as to arrest the travel of the box 22 from the casing 5 when such travel has reached a desired limit.

Within the box 22 there is a removable 65 container 25 which may be of a size to fit

quite snugly within the box 22 and yet without any tight engagement therein, so that the container may be removed through what constitutes the rear end of the box, which end is left open, at any time such removal 70 may be desired. To facilitate the removal of the container 25 it is provided on the rear wall with a manipulating handle 26, which handle may be taken as indicative of any manipulating means. To facilitate the 75 cleaning of the box 25 the lower edges are rounded, as shown at 27 and 28, respectively.

The top of the container 25 is open and the box 22 is provided with a hinged cover 29 in the form of a seat, the hinge connections being shown at 30, and these hinge connections are made to extend a distance above the top surface of the seat 29, so as to be engaged by a latch member 31 hinged at one edge to the under face of the top 7 80 of the casing 5 adjacent to the door 15, and this latch member 31, which may be in the general form of a flap to hang pendently from the top 7, is so related to the seat 29 as to readily permit a movement of the box 90 22 through the passage 3 to the interior of the room, and when the inward movement of the box 22 has been reached the latch 31 drops behind the hinges 30 to hold the box in the extended position. In order to return the box 22 into the casing 5 it is necessary to lift the latch member 31 out of engagement with the hinges 30.

The door 15 is so constrained toward the closed position by weights 32 carried by 100 cords 33, one end of each of which is made fast to a corresponding side 12, as indicated at 34, and is passed around a pulley 35 on the weight 32, thence over a direction-changing pulley 36 on the corresponding side 12 105 near the top thereof and close to the slide 11, and from the pulley 36 the cord 33 is carried through the casing 5 to the door 15 where it is made fast to the door, as indicated at 37. When the door 15 is moved 110 to the lowered or horizontal position, the weights 32 are raised and when the door is released the weights 32 immediately move the door to the upright closed position shown in Fig. 2. The box 22 is also constrained 115 toward the interior of the casing 5 by weights 38 arranged on opposite sides of the box within the casing 5. These weights are each suspended by a cord 39 made fast to a corresponding side 12, as indicated at 120 40, and carried from the point of fastening about a pulley 41 on the weight, thence about another pulley 42 on the corresponding side 12 near the top thereof and thence to a suitable point on the corresponding side 125 of the box, as shown at 43. When the box 15 is drawn out of the casing 5 the weights 38 are raised, but the box is held in the withdrawn position by the latch 31. When released from the latch 31 the box will return 130

into the casing 5 by the action of the weights 38.

The door 15 is in the lowered position by the weight of the box 22 and when this box is moved from the lowered door 15 into the casing 5 the door rises by the action of the weights 32 to the closed position.

To ventilate the interior of the casing 5 the door 15 is provided with ventilating openings 44 near its lower edge, and the box 22 is also provided with ventilating openings 45. These ventilating openings are covered with gauze or other screening material 46 to prevent access of insects to the interior of the casing 5. Furthermore, within the box 22 there is provided a receptacle 47 for some suitable deodorant.

To facilitate the withdrawal of the box 22 from the casing 5 the box is provided with a manipulating handle 48.

In order to support the casing 5 where it is not convenient to provide underriding brackets, straps 49 are each made fast at one end to each side 12 of the casing near the outer end thereof, a bolt 50 providing a convenient means for the purpose. The other end of each strap 49 is secured to the outer face of the wall 1 at a sufficiently high point above the casing 5 to properly support it.

The structure of Figs. 4, 5 and 6 is in many respects similar to the structure of Figs. 1, 2 and 3, but differs in some respects. There is present a wall 1 having a passage 3 therethrough opening into a compartment of which only the floor 2 is shown. A casing 5 is provided as in Figs. 1, 2 and 3, and this casing has a bottom portion 4^a similar to the shelf 4 of Fig. 2. The casing 5 has a top portion 7 with an opening 8, collar 9, and vent pipe 10, as in the other figures, and the casing has also a rear slide 11 and is supported by straps 49 like the structure of Figs. 1, 2 and 3. The passage 3 in the structure of Figs. 4, 5 and 6 is normally closed by a door 15^a, but instead of having hinges 16 at the bottom of the door, there are other hinges 16^a at one upright side of the door, and these hinges are preferably spring hinges tending at all times to close the door. A knob 17 serves as a means whereby the door may be readily opened and near the bottom the door has ventilating passages 44 covered by screen material 46, as in the structure of Figs. 1, 2 and 3. The door 15^a does not rise quite to the height of the casing 5 and from the top of the door over that portion of the passage 3 which would otherwise be exposed inside of the building there is a hood 51 having ventilating passages 52, the hood opening into the passage 3 and the latter opening through the exterior of the wall 1.

The casing 5 normally houses a box 22^a which in most respects is similar to the box

22, and needs no particular description. Instead of rollers 23 the box 22^a is provided with feet 23^a. Other parts of the box 22^a which correspond to the box 22 are given the same reference numerals in Figs. 4, 5 and 6 as appear in Figs. 1, 2 and 3.

The box 22^a is carried on opposite sides by links 53 pivotally supported at the lower ends, as shown at 54, and at the upper ends connected to the box 22^a by pivots 55. The links 53 are spaced apart in the direction of the depth of the casing 5 by a distance nearly equal to the depth of the box 22^a from front to rear. The links 53 are longer than the height of the box and consequently when the box 22^a is housed within the casing 5 with the links 53 upright the bottom of the box is elevated a considerable distance above the bottom 4^a of the casing 5. About midway of the lengths of the links 53 they are connected together by a spacing link 56. There are two sets of links 53, one on each side of the box, and these links constitute a parallel motion support for the box whereby when the links 53 are rocked on the pivots 54 the box is lowered and projected out of the casing 5 or elevated and moved into the casing 5 in accordance with the direction of movement. Because the box 22^a is thus elevated and lowered the casing 5 is made correspondingly high, and higher than in the arrangement shown in Figs. 1, 2 and 3. Otherwise the box is quite similar to the arrangement of Figs. 1, 2 and 3. In order to impart to the box 22^a a normal constraint to move into and remain in the casing 5, weights 57 are provided, each weight being connected to a cord 58 carried over a pulley 59 on the side of the casing near the upper rear corner thereof, and then to an eye 60 or other fastening means which may be coincident with the corresponding pivots 55 connecting the rear links 53 to the box 22^a.

Since the door 15^a of the structure of Figs. 4, 5 and 6 is hinged along one long side, and swings outwardly into one side of the passage 3, the floor 2 and the bottom 4^a of the casing 5 may be arranged on a level, but the parts may be proportioned so that such particular arrangement is not necessary.

In the structure of Figs. 4, 5 and 6, the sides of the casing 5 represented at 12^a may be of metal instead of wood.

What is claimed is:—

1. A dry closet comprising a casing having opposite ends provided with closures with the closure at one end having a normal constraint toward the closed position, a box normally housed within the casing and movable out therefrom through the end provided with the closure having a normal closing constraint, said box also being provided with means constraining it to move into the casing and open at the end remote from that

end of the casing into and out of which the box is movable, and a receptacle within the box removable therefrom through the open end of the box and that end of the casing remote from the end provided with the closure having the normal constraint toward the closed position.

2. A dry closet comprising a casing having closures at opposite ends with one closure provided with means normally constraining it toward the closed position, a box normally housed in the casing and movable into and out of the casing through that end provided with the normally constrained closure, said box having a seat and also having one end open, and a receptacle within the box movable therefrom through the open end of the box and from the casing through that end of the latter remote from the end having the normally constrained closure.

3. A dry closet comprising a casing adapted to be placed on one side of a division wall having an opening therethrough, a door adapted to be placed on the other side of the division wall to cover the opening therethrough, a box movable into and out of the casing and having means imparting to it a normal constraint to move into the casing, a seat for the top of the box, and a removable receptacle normally within the box, said box having the end remote from the door end of the casing open and the receptacle being removable from the box through said open end of the latter.

4. A dry closet comprising a casing adapted to be placed on one side of a division wall having an opening therethrough, a door adapted to be placed on the other side of the division wall to cover the opening therethrough, a box movable into and out of the casing and having means imparting to it a normal constraint to move into the casing, a seat for the top of the box, and a removable receptacle normally within the box, said box having the end remote from the door end of the casing open and the receptacle being removable from the box through said open end of the latter, and said casing having the end remote from that adapted to the division wall provided with a readily removable closure of a size to admit of the removal of the receptacle from the box while the latter is within the casing.

5. A dry closet comprising a casing having one end larger than the other and open at both ends, a closure for each end with the closure at the larger end having means constraining it toward the closed position, a box normally housed in the casing and movable therefrom through the larger end of the casing and provided with means normally constraining it to move into the casing, said box having the end toward the smaller end of the casing open, a seat for the box, and

a receptacle within the box movable therefrom through said open end of the box and the smaller end of the casing.

6. A dry closet comprising a casing adapted to be placed on one side of a division wall having an opening therethrough, a door adapted to the other side of the wall to constitute a closure for the corresponding end of the casing, said door having means imparting to it a normal constraint toward the closed position, and a box adapted to the interior of the casing and provided with means imparting to it a normal constraint to move into and remain in the casing, the box being provided with a receptacle removable through that end of the box remote from the door and open toward the top of the box, and the casing being provided with a readily removable closure for the end remote from the door and of a size to admit of the removal of the receptacle from the box through said end of the casing.

7. A dry closet comprising a casing adapted to be located at the exterior of a wall having an opening therethrough with the casing coincident with said opening, a door constituting a closure for the inner end of the opening through the wall and provided with means for imparting to it a normal constraint toward the closed position, a box provided with a seat and adapted to be housed in the casing, means imparting to the box a normal constraint to move into and remain in the casing, and a ventilating stack carried by and rising from the casing exterior to the wall, the door and box being provided with ventilating passages for co-operation with the ventilating stack.

8. A dry closet comprising a casing adapted to be applied to a wall with a passage therethrough at said passage and extend outwardly from the wall, supporting means for the casing connected to the wall, a ventilating stack rising from the top of the casing, a box normally housed in the casing and provided with a seat and with ventilating passages leading to the interior of the box, said box having one end open, means for imparting to the box a normal constraint to remain in the casing and to return thereto when withdrawn from the casing, a receptacle adapted to the interior of the box and removable through the rear of the box, the rear of the casing having a removable closure of a size to permit the removal of the receptacle from the box and from the casing, and a door adapted to the interior of the wall to constitute a closure for the passage through the wall and for the corresponding end of the receptacle, said door having means imparting to it a normal constraint to move to and remain in the closed position.

9. A dry closet comprising a casing adapted to be placed exterior to a wall hav-

- ing a passage therethrough with one end of the casing at said passage, a door constituting a closure for the interior end of the passage through the wall and movable from a normal upright position to a substantially horizontal position coincident with the bottom of the interior of the casing, and a box adapted to the interior of the casing and movable therefrom on to the lowered door, 10 said box being provided with a seat and with a receptacle and movable from within the casing through the passage in the wall on to the lowered door to hold the latter in the lowered position.
- 15 10. A dry closet comprising a casing adapted to be placed exterior to a wall having a passage therethrough with one end of the casing at said passage, a door constituting a closure for the interior end of the passage through the wall and movable from a normal upright position to a substantially horizontal position coincident with the bottom of the interior of the casing, and a box 20 adapted to the interior of the casing and movable therefrom on to the lowered door, said box being provided with a seat and with a receptacle and movable from within the casing through the passage in the wall on to the lowered door to hold the latter in the lowered position, the casing and box having coacting members for holding the box in the projected position and the box and door each having means constraining 25 the box to move into and remain within the receptacle and the door to move to and remain in the closed position, said constraining means comprising weights and cords and direction-changing devices for the 30 cords.
- 30 25. A dry closet comprising a casing adapted to be placed exterior to a wall having a passage therethrough with one end of the casing at said passage, a door constituting a closure for the interior end of the passage through the wall and movable from a normal upright position to a substantially horizontal position coincident with the bottom of the interior of the casing, and a box 35 adapted to the interior of the casing and movable therefrom on to the lowered door, said box being provided with a seat and with a receptacle and movable from within the casing through the passage in the wall on to the lowered door to hold the latter in the lowered position, the casing and box having coacting members for holding the box in the projected position and the box and door each having means constraining 40 the box to move into and remain within the receptacle and the door to move to and remain in the closed position, said constraining means comprising weights and cords and direction-changing devices for the 45 cords.

In testimony, that I claim the foregoing as my own, I have hereto affixed my signature in the presence of two witnesses.
